[57] **ABSTRACT**

Apparatus for sinking a vertical shaft includes a tubular cutting head. The cutting head is positioned in a guide collar in the earth and is rotated by a rotary drive means to bore the shaft into the ground. A crane and clam shell bucket may be used to remove the spoil generated by this cutting action and to attach additional sections of casing to the cutting head. Means are provided to both urge the cutting head into the ground and to extract it from the shaft.

MACHINE FOR SINKING VERTICAL SHAFTS

BACKGROUND OF THE INVENTION

1. Field of the Invention

The present invention relates to earth working equipment for driving tubes or casings into the ground in a generally vertical direction.

2. Description of the Prior Art

It is often desired to sink vertical shafts of considerable diameter, for example, 7 to 24 feet, into the earth. A typical application is the provision of work shafts in conjunction with the construction of subterranean tunnels. Such work shafts permit the provision and removal of equipment, and the discharge of muck and other debris from the tunnel during construction. Similarly, man holes permit the entry and egress of workers, both during and after construction. Vertical shafts, or drop sewers, are also required between horizontal sewers located at different levels. The depth of vertical shafts of the foregoing types may typically range from 60 to 100 feet up to a maximum of 200 feet or more.

In the past, vertical shafts have been constructed by conventional earth working techniques. A hole is dug in the ground having a circumference approximately the same as that intended for the vertical shaft. The depth of the hole is determined by the subsidence characteristics of the soil. The hole is then lined with wood, concrete, or metal walls, after which the hole is dug deeper, the wall construction continued, and so on until the shaft has been extended to the desired depth.

It will be appreciated that these conventional techniques are both time consuming and expensive, requiring large amounts of equipment and large numbers of men. Further, the presence of workmen is required in the hole during the sinking of the shaft. The risk of injury is quite high. Insurance, and other similar costs, are correspondingly high.

In the case of an access or work shaft, it may subsequently be desired to remove the shaft walls after the subterranean work has been completed. For example, upon the completion of a tunnel construction, concrete forms may be placed in the access shaft and a small manhole shaft poured. The access shaft walls are then removed and the shaft backfilled around the poured manhole casing. In other instances, the bottom of the access shaft may be sealed, the walls removed and the entire shaft refilled. Conventional earth working techniques and equipment also render this aspect of vertical shaft construction expensive, time consuming, and hazardous because of the necessity of placing men in the shaft, and for other reasons.

SUMMARY OF THE PRESENT INVENTION

It is, therefore, the object of the present invention to provide a machine for rapidly, inexpensively, and safely sinking vertical shafts.

The machine of the present invention is capable of sinking shafts of large diameter. The machine is simple in construction, utilizing the machine's own weight to assist a rotary cutter in boring the shaft. As the depth of the shaft increases, the weight of the machine increases due to the attachment of additional sections of shaft lining casing, thereby increasing the effectiveness of the boring action of the machine. The machine may employ an oscillatory rotary cutting action which facil-

tates maintaining the plumb and line of the vertical shaft.

The machine is operable on a continuous basis with a small crew. It may be particularly noted that the machine does not require the presence of workmen in the shaft during either the sinking of the shaft or removal of the shaft lining casing, thereby providing a high degree of safety to its operation. The machine is portable, facilitating movement of the apparatus from one work site to another.

Briefly, the vertical shaft sinking machine of the present invention includes a guide collar locatable in the earth along the axis of the shaft. A tubular cutting head having a cutting bit on the lower edge thereof is rotatably mounted in the guide collar. Extensible means, such as a plurality of hydraulic cylinders coupled between the guide collar and the exterior of the cutting head, are provided for rotating the cutting head in the guide collar to sink the shaft. Because the rotary drive means is coupled to the outside of the cutting head, the interior of the cutting head is free from obstruction, allowing removal of the spoil during operation of the cutting head.

As the sinking of the shaft progresses, additional sections of casing are attached to the cutting head. The machine also includes means for retracting the casings through the guide collar.

BRIEF DESCRIPTION OF THE DRAWING

FIG. 1 is a partially cut away view of the machine for sinking vertical shafts of the present invention.

FIG. 2 is a top view of the vertical shaft sinking machine taken along line 2-2 of FIG. 1, said view also being partially cut away to reveal certain details of the machine's construction.

FIG. 3 is an enlarged partial view of clamping elements of the machine, said view being partially cut away to reveal the details of the elements.

FIG. 4 is a partial plan view of a portion of the machine showing means by which the rotary drive means for the machine may be adjustably positioned on the guide collar.

FIG. 5 is a partial elevational view of the machine of the present invention showing means for extracting portions of the machine from the shaft.

FIG. 6 is a cross sectional view taken along the line 6-6 of FIG. 5 showing the use of portions of the machine to assist in affixing additional sections of casing to the cutting head of the machine.

FIG. 7 is an elevational view showing the use of a crane in conjunction with the machine of the present invention. The crane may be used to position additional sections of casing, as shown in FIG. 7; to remove spoil from the interior of the machine; or to position portions of, or assemble, the machine.

DESCRIPTION OF THE PREFERRED EMBODIMENT

The present invention employs cutting head 12 to sink the vertical shaft. Cutting head 12 is comprised of a section of casing or tubing 14, similar to that used to line the vertical shaft as it is sunk. An annular cutting bit 16 may incorporate any commonly available rotary cutter construction suitable for the type of soil into which the vertical shaft is being sunk. As will hereinafter be noted, it is desirable that cutting bit 16 afford a penetrating action in either direction of rotation. Serrat-

ing the lower edge of cutting bit 16, as shown in FIG. 1, to form teeth 18 has been found to provide a cutting bit of satisfactory construction.

Guide collar 20 is positioned in the earth along the bore of the vertical shaft to form a journal for the rotation of cutting head 12. Guide collar 20 includes tubular liner 22. In order to both provide guidance and permit the necessary rotation of the cutting head 12, it has been found desirable to make the diameter of tubular liner 22 larger than the diameter of cutting head 12 by an amount necessary to achieve these objectives. The difference in diameters may typically be 1 inch but will vary depending on the diameters of cutting head 12, liner 22, and other factors.

Tubular liner 22 is cast in concrete pad 24. Tubular liner 22 may be provided with flanges 26 to secure the liner in concrete pad 24 against the circumferential forces exerted during the rotation of cutting head 12. Circumferential reinforcing bars 28 may be inserted in the concrete pad to reinforce the pad.

To lubricate casing 12 in its engagement with liner 22 and with the earth, a lubricating slurry of bentonite, or the like, may be provided. For injecting the slurry, it has been found desirable to mount a plurality of circumferentially spaced pipes 30 along the inside of casing 14 of cutting head 12. The pipes empty on the exterior of the cutting head 12, above cutting bit 16, as shown in FIG. 1. The upper ends of pipes 30 contain flexible hoses 31 and couplings 33 to accommodate the movement of cutting head 12. Couplings 33 also facilitate the attachment of additional sections of casing to cutting head 12, as hereinafter described.

One or more pipes 32 may be provided in concrete pad 24 on the periphery of tubular liner 22 so that the presence and amount of slurry may be ascertained either by the discharge from the upper end of pipes 32 or by an appropriate instrument located in the pipe.

To provide rotation to cutting head 12 in guide collar 20 a clamping ring having a rotary drive means associated therewith engages the portion of cutting head 12 which extends above guide collar 20. Clamping ring 40, hereinafter sometimes called the lower clamping ring, rests on concrete pad 24 and the concrete pad may be provided with wear or bearing plate 41 to reduce the friction and wear occurring when clamping ring 40 is rotated, as hereinafter described. Clamping ring 40, which may be of hollow box-like construction, as shown in FIG. 1, is comprised of two semi-circular halves 40a and 40b pivotally joined at hinge 42. Ring 40 is clamped on cutting head 12 by toggle mechanisms 44a and 44b located diametrically opposite hinge 42. The toggle mechanisms are shown in detail in FIG. 3. In as much as the toggle mechanisms are similar, only one such mechanism 44a is described in detail.

Toggle mechanism 44a includes bar 46 having one end connected to pin 48 in ring half 40b. The other end of bar 46 is pivotally connected to toggle 50 which in turn is pivotally mounted on ring half 40a by pin 51. The arm 52 of toggle 50 is connected to one end of hydraulic cylindrical 54, the other end of which is connected to ring half 40a. Toggle mechanism 44a is preferably mounted inside the ring and an opening is provided in the outer wall 56 of ring half 40a for toggle arm 52 and hydraulic cylinder 54.

The second toggle mechanism 44b may be positioned below toggle mechanism 44a. One end of the bar of toggle mechanism 44b is connected to ring half 40a and

toggle 58 and hydraulic cylinder 60 are mounted on ring half 40b.

By extending the pistons of hydraulic cylinders 54 and 60, toggles 50 and 58 are pivoted to draw ring halves 40a and 40b together and clamp lower clamping ring 40 on casing 14 of cutting head 12. By retracting the pistons of hydraulic cylinders 54 and 60, toggles 50 and 58 are pivoted to push ring halves 40a and 40b apart and release lower clamping ring 40 from cutting head 12.

Rotation of lower clamping ring 40 and cutting head 12 may be provided by an extensible means having one or more extensible elements. This may typically comprise two pairs of opposed hydraulic cylinders having extensible rams. Hydraulic cylinders 62 and 64 each have one end of the cylinder body anchored in concrete pad 24 and one end of the ram connected to a common journal 59 on lower clamping ring 40. Similarly, hydraulic cylinders 65 and 68 each have one end of the cylinder body anchored in concrete pad 24 and one end of the ram connected to a common journal 61 on ring 40. The journal 59 for hydraulic cylinders 62 and 64 may be diametrically opposite the journal 61 for hydraulic cylinders 66 and 68 on lower clamping ring 40.

The hydraulic cylinders are joined to concrete pad 24 in a manner which allows horizontal adjustment of the hydraulic cylinder ends, thereby permitting positional correction of the vertical shaft. Such positional corrections include corrections to line which insure that the machine and the shaft are located at the desired location on the ground, for example, with the axis of the shaft in alignment with the surveyed center of the shaft. The horizontal correction of the cylinders may also assist in corrections to plumb which insure that the machine, and hence the shaft sunk thereby, has the desired degree of verticality.

The affixation of the hydraulic cylinders to concrete pad 24 may best be seen in FIG. 4. A plurality of threaded rods 63 are embedded in concrete pad 24 adjacent the ends of each of the cylinders. FIG. 4 shows the use of four such rods in connection with cylinder 62. Plate 65 having four slots 67 mating with threaded rods 63 is placed over the threaded rods and retained thereon by nuts 69. Gudgeon 71 mounted on the end of hydraulic cylinder 62 fits over anchor post 73 mounted on plate 65 to join the hydraulic cylinder to the concrete pad.

The ends of hydraulic cylinders 64, 66, and 68 are anchored in concrete pad 24 in a manner similar to that described in detail in connection with hydraulic cylinder 62 as shown in FIG. 2. By loosening nuts 69 on threaded rods 63, the position of the hydraulic cylinders on concrete anchor pad 24 and hence the position of cutting head 12 in tubular liner 22 may be altered to correct locational or other errors.

By extending the rams of hydraulic cylinders 62 and 68, lower clamping ring 40 and cutting head 12 are rotated in the counter-clockwise direction when viewed as in FIG. 2. By extending the rams of hydraulic cylinders 64 and 66, lower clamping ring 40 and cutting head 12 are rotated in the clockwise direction. In some instances, it may be desirable to use less than four cylinders. For example, only one of cylinders 62 and 64 and one of cylinders 66 and 68 may be utilized or, in some cases, only a single cylinder or one pair of cylinders 62 and 64 or 66 and 68 may be employed. The hy-

draulic cylinders may be single or double acting, as desired.

A second, or upper, clamping ring 70, mounted above clamping ring 40, also engages the portion of cutting head casing 14 which extends above guide collar 20, as shown in FIG. 1. Upper clamping ring 70 may be similar in construction to lower clamping ring 40 to include two semi-circular halves 70a and 70b of hollow box-like construction, pivotally joined at hinge 72. Upper clamping ring 70 is clamped on cutting head casing 14 by toggle mechanisms 74a and 74b located diametrically opposite hinge 72 and operable by hydraulic cylinders 73 and 75, respectively. Toggle mechanisms 74a and 74b may be similar in construction and operation to toggle mechanisms 44a and 44b utilized in connection with lower clamping ring 40.

Upper clamping ring 70 is separated from lower clamping ring 40 by a plurality of circumferentially spaced hydraulic jacks 76, the housings of which are affixed to lower clamping ring 40 and the terms 78 of which abut the underside of upper clamping ring 70. This construction may be seen in FIGS. 5 and 6. Also, as shown most clearly in FIGS. 5 and 6, a plurality of peripheral slots 80 are provided in the walls of upper clamping ring 70. No rotary drive means is coupled to upper clamping ring 70.

Cutting head 12 is urged into contact with the earth to obtain the desired cutting action by the weight of cutting head 12. Because of the heavy construction of cutting head 12, clamping rings 40 and 70, etc., the weight of this apparatus will, in many cases, be fully sufficient as a vertical driving force. In other cases, the intrinsic weight of cutting head 12, clamping rings 40 and 70, etc., may be augmented with an additional circular weight 34 placed on the upper edge of cutting head casing 14 as by crane 82 shown in FIG. 7. A notch 36 is provided in weight 34 to retain the weight on the cutting head casing. It will be appreciated that as the sinking of the shaft progresses and additional sections of casing are affixed to cutting head casing 14, the weight of the machine increases, increasing the vertical force and the effectiveness of the machine's cutting action.

A power supply, not shown, is provided to energize the various elements of shaft sinking machine 10. The power supply includes a hydraulic pressure system with a source of hydraulic pressure such as a conventional hydraulic pump. The hydraulic pressure system is used to extend and retract rotation producing hydraulic cylinders 62, 64, 66 and 68 and to extend and retract hydraulic lift jacks 76. The operation of these elements is coordinated with the operation of hydraulic cylinders 54 and 60 and 73 and 75 in the clamping ring toggle mechanisms 44 and 74. A slurry pump, coupled to hoses 31, is also provided.

Vertical shaft sinking machine 10 also includes a means to remove the spoil generated by the sinking of the vertical shaft. This means may comprise the crane 82 shown in FIG. 7, positioned adjacent concrete pad 24 and having clam shell bucket 84 or other scoop means which may be lowered down the vertical shaft to pick up the spoil and then raised out of the shaft to remove it. Crane 82 may also be used to assemble machine 10, to apply and remove weight 34, and to position additional sections of casing for attachment to cutting head 12.

To commence the sinking of the vertical shaft, a hole dug in the surface of the earth in the area in which the shaft is to be driven. Cutting head 12 is inserted in the hole so that cutting bit 16 is in contact with the bottom of the hole and the axis of the cutting head lies along the bore of the shaft. Liner 22 is placed over cutting head 12 and concrete pad 24 is poured around the exterior of the liner. Pipes 32 and threaded rods 63 for hydraulic cylinders 62 through 68 may be appropriately positioned prior to the pouring of the concrete pad.

Clamping ring 40 is hoisted over the portions of cutting head casing 14 extending above concrete pad 24, as by means of crane 82. With hydraulic cylinders 54 and 60 retracted to move toggle mechanisms 44a and 44b to the unclamped position the ring is lowered over cutting head 12 to rest on wear plate 41. One end of each of hydraulic cylinders 62 through 68 is anchored on rods 63 embedded in concrete pad 24 in the manner shown in FIG. 4 and described above. The other ends of the hydraulic cylinders are joined to journals 59 and 61 on lower clamping ring 40. Various hydraulic cylinders associated with lower clamping ring 40 are connected to the source of hydraulic pressure and hydraulic cylinders 54 and 60 are extended to clamp the ring on the cutting head casing. The rams 78 of hydraulic jacks 76 are also extended. Pipes 31 are connected to the slurry pump.

Upper clamping ring 70 may then be placed on cutting head casing 14 by procedures similar to that employed in conjunction with lower clamping ring 40 to rest on the extended rams 78 of jacks 76. Hydraulic cylinders 73 and 75 of toggle mechanisms 74a and 74b are then connected to the hydraulic pressure system and the cylinders are extended to clamp ring 70 on cutting head casing 14. Thereafter, the rams 78 of hydraulic jack 76 may be retracted to leave upper clamping ring 70 positioned above lower clamping ring 40 on cutting head casing 14.

Weight 34 may then be placed on the upper edge of cutting head 12 as by means of crane 82.

The slurry pump is started to provide a lubricating slurry around casing 14.

Hydraulic cylinders 62 through 68 are then operated to rotate lower clamping ring 40 and cutting head 12. Two modes of periodic rotating action may be provided — a bidirectional, oscillating mode and a unidirectional mode. The type of rotating action employed is selected in accordance with the type of soil through which the shaft is being sunk, the construction of cutting bit 16, etc. To oscillate cutting head 12 first in one direction and then in the other, hydraulic cylinders 62 through 68 are initially extended to move cutting head 12 in the counter clockwise direction. Thereafter hydraulic cylinders 64 and 66 are extended to move cutting head 12 clockwise. Lower clamping ring 40 rides on wear plate 41 during rotation.

In a unidirectional rotation operating mode, one pair of the hydraulic cylinders, for example, hydraulic cylinders 62 and 68 are initially extended to rotate cutting head 12 in the counter clockwise direction. Hydraulic cylinders 54 and 60 are then retracted to loosen lower clamping ring 40 on cutting head 12. Hydraulic cylinders 64 and 66 are extended to rotate lower clamping ring 40, but not cutting head 12, in the clockwise direction. Hydraulic cylinders 54 and 60 are then extended to reclamp lower clamping ring 40 on cutting head 12,

and hydraulic cylinders 62 and 68 are re-extended to continue the counter clockwise rotation of cutting head 12. By an analogous operation and coordination of hydraulic cylinders 62 through 68 and hydraulic cylinders 54 and 60 in toggle mechanisms 44a and 44b, clockwise rotation of cutting head 12 may be produced.

While the oscillatory mode of rotary action is presently preferred, since the alternating cutting directions tend to prevent displacement of the axis of the shaft from its desired location, machine 10 of the present invention also facilitates use of a constant rotary cutting direction by overcoming difficulties previously encountered with this technique. With a constant or unidirectional rotary cutting direction, the torque applied to cutting head 12 as the shaft is sunk has, in the past, tended to displace the axis from its intended course. However, through the use of guide collar 20, the machine of the present invention permits a unidirectional rotary cutting direction while at the same time minimizing or eliminating the tendency for the shaft to drift off course.

After several oscillatory or unidirectional incremental rotary motions of cutting head 12, hydraulic cylinders 54 and 60 are retracted to loosen lower clamping ring 40 and allow cutting head 12 to descend, driven by its weight, the weight of clamping ring 70, and the weight of weight 34, if applied. Hydraulic cylinders 54 and 60 are then extended to reclamp lower clamping ring 40 and the rotation of cutting head 12 is resumed to recommence sinking the vertical shaft. The spoil which accumulates inside the cutting head as a result of the cutting action of cutting bit 16 and the descent of cutting head 12 is removed by clam shell bucket 84. Spoil removal may be carried out while cutting head 12 is being rotated, if desired.

As cutting head 12 descends, upper clamping ring 70 which is clamped on casing 14, approaches the upper ends of rams 78 of hydraulic jacks 76 located on lower clamping ring 40. When this occurs, the rotation of cutting head 12 is stopped. The rams 78 of hydraulic jacks 76 are extended into contact with the lower surface of upper clamping ring 70. Hydraulic cylinders 73 and 75 of toggle mechanisms 74a and 74b are then retracted to release upper clamping ring 70 from cutting head casing 14 and rams 78 operated to their full extension to raise upper clamping ring 70 along cutting head casing 14. Hydraulic cylinders 73 and 75 are extended to reclamp upper clamping ring 70 on cutting head casing 14 and rams 78 retracted. The rotary operation of vertical shaft sinking machine 10 then recommences to resume sinking the vertical shaft. Each time upper clamping ring 70 approaches lower clamping ring 40, the above described operation is repeated.

When cutting head 12 has sunk so that upper clamping ring 70 can no longer be raised along casing 14 of cutting head 12, an additional section of casing must be added. Weight 34, if in use, is removed and slurry hoses 31 disconnected. Lower clamping ring 40 remains clamped to cutting head 12 as the rams 78 of hydraulic jacks 76 are brought into contact with the lower surface clamping ring 70. Upper clamping ring 70 is then loosened. Hydraulic jacks 76 are operated to extend rams 78 to position upper clamping ring 70 so that a portion of its extends beyond the upper edge of casing 14. A new section of casing 14a is then raised over cutting head 12, as shown in FIG. 7, and lowered into the

exposed portion of ring 70. Clamping ring 70 is tightened to hold casings 14 and 14a together and to insure the concentricity of the two sections. The sections of casing are then tack welded through slots 80, as shown in FIGS. 5 and 6. Thereafter upper clamping ring 70 is unclamped, rams 78 retracted to lower the ring and expose the casing joint, the upper clamping ring 70 reclamped. The casings are welded together around their entire circumference, weight 34, if needed, replaced, slurry hoses 31 reconnected and the operation of shaft sinking machine 10 resumed to further sink the shaft.

Depending on the depth of the shaft, the size and thickness of the casing, etc., it may be necessary to provide vertically spaced reinforcing rings on the inner periphery of the shaft casing. These rings can be installed in the casings prior to use or can be positioned as the sinking of the shaft progresses.

In the event the vertical shaft drifts off line or out of plumb, these errors may be corrected by altering the position of hydraulic cylinders 62 through 68 adjusting the position of anchor plates 65 on rods 63 in the manner described above, and/or by partially extracting cutting head 12 from the shaft, correcting the error, and restarting the cutting head. This latter operation may be accomplished in the following manner. When upper clamping ring 70 approaches the upper ends of rams 78 of hydraulic jacks 76, the rotation of cutting head 12 is stopped. Lower clamping ring 70 is unclamped from cutting head 12. Rams 78 of hydraulic jacks 76 are then extended to full extension. In as much as upper clamping ring 70 remains clamped to cutting head casing 14, the extension of rams 78 raises cutting head 12 with upper clamping ring 70. Lower clamping ring 40 is then reclamped on casing 14 of cutting head 12 to retain cutting head 12 in the extracted position, and the hydraulic jacks are retracted. The position of anchor plates 65 may be adjusted or other corrections may be made. It will be appreciated that only selected ones of hydraulic jacks 76 may be extended, for example, to raise one side of cutting head 12 to take corrective action. The rotation of cutting head 12 is then resumed to recommence sinking the vertical shaft.

In the event a single extension of hydraulic jacks 76 does not provide the desired amount of extraction, upper clamping ring 70 may be unclamped prior to the retraction of hydraulic jacks 76 for lowering along casing 14 of cutting head 12 as the hydraulic jacks are retracted. Upper clamping ring 70 is reclamped in the lower position, lower clamping ring 40 unclamped, and hydraulic jacks 76 extended to continue the extraction of cutting head 12.

In the instance in which vertical shaft casing 14 is to be removed, the above described extractive operation is repeated until the casing is completely removed from the shaft. In many cases, the vertical shaft will have joined a subterranean horizontal tunnel through which cutting bit 16 will have been removed. If not, the cutting bit 16 is disassembled. Once this has been accomplished, workmen need not enter the shaft during the removal of the shaft casing. The extraction of the shaft casing is carried out through the coordinated operation of lower clamping ring 40, upper clamping ring 70 and hydraulic jacks 76. If necessary, the shaft casing may be rotated during extraction. As the sections of welded casing emerge from the shaft, they are cut apart with torch or other means. When the casings have been completely removed, the shaft is backfilled. Concrete

pad 24 may be broken up or left as part of the surface structure.

It will be appreciated that the hydraulic pressure system for vertical shaft sinking machine 10 may include means such as limit switches, solenoid operated valves, and the like, to render all or portions of the operation of machine 10 automatic or semi-automatic. For example, the oscillatory rotation of cutting head 12 may be rendered automatic by coordinating the operation of hydraulic cylinders 62 and 68 and hydraulic cylinders 64 and 66. To provide automatic unidirectional rotary motion, the operation of these hydraulic cylinders may be coordinated with the operation of hydraulic cylinders 54 and 60 in toggle mechanisms 44a and 44b which clamp and unclamp lower clamping ring 40. Similarly, by coordinating the clamping and unclamping of lower clamping ring 40 and upper clamping ring 70 and the extension and retraction of hydraulic jacks 76, the control of the vertical movement of the casings may be rendered automatic.

Various modes of carrying out the invention are contemplated as being within the scope of the following claims particularly pointing out and distinctly claiming the subject matter which is regarded as the invention.

I claim:

1. Earth working apparatus for sinking a shaft casing into the earth, said apparatus comprising:

guide collar means extendible below the surface of the earth at the place of sinking the shaft and suitable for restraining engagement with the earth, said guide collar means having an exposed upper surface; a tubular cutting head extending through, and rotatably journaled in, said guide collar means, said head having a cutting bit on the lower edge thereof; a clamping ring resting on said exposed upper surface of said collar means and rotatable with respect to said guide collar means, said clamping ring being engageable with the exterior periphery of a portion of the cutting head extending above said guide collar means for rotating the cutting head while preventing axial movement of the cutting head with respect to the guide collar when engaged; and drive means mounted on the upper surface of said guide collar means and coupled between said clamping ring and said guide collar means for periodically rotating said clamping ring and said cutting head in said guide collar means.

2. The earth working apparatus according to claim 1 wherein said clamping ring includes hinged circumferential segments and a clamping coupling means for pivoting the segments between a closed, cutting head engaging condition, and an open, non engaging condition.

3. The earth working apparatus according to claim 1 wherein said tubular cutting head has an upper edge adapted to receive a downwardly exerted force and said apparatus includes a weight positioned on said upper edge.

4. The earth working apparatus according to claim 1 including means for removing spoil from the interior of the cutting head.

5. The earth working apparatus according to claim 1 wherein said cutting head has additional sections of casing attached thereto as the sinking of the shaft progresses.

6. The earth working apparatus according to claim 5 including means for erecting said casing sections over

said cutting head in vertical alignment therewith for attachment to said cutting head.

7. The earth working apparatus according to claim 1 further including means for supplying lubricant to said cutting head for facilitating the sinking of the shaft.

8. The earth working apparatus according to claim 7 wherein said lubricant supplying means comprises pipes mounted in the cutting head and opening adjacent said cutting bit.

9. The earth working apparatus according to claim 1 wherein said drive means comprises extensible means anchored on the upper surface of said guide collar means and tangentially coupled to said clamping ring for providing oscillatory rotation to the latter.

10. The earth working apparatus according to claim 9 wherein said extensible means comprises at least one extensible element anchored in said guide collar means and tangentially coupled to said clamping ring.

11. The earth working apparatus according to claim 10 wherein said extensible element comprises a hydraulic cylinder.

12. The earth working apparatus according to claim 10 wherein said tubular cutting head is radially movable within said guide collar means and said extensible means is adjustably anchored on said guide means for locating said cutting head within said guide collar means.

13. The earth working apparatus according to claim 10 wherein said extensible means comprises a plurality of extensible elements anchored in said guide collar means and tangentially coupled to said clamping ring.

14. The earth working apparatus according to claim 13 wherein said extensible means includes first and second pairs of opposed extensible elements coupled for reciprocal operation, said pairs of extensible elements having a reciprocally movable portions coupled to said clamping ring for providing oscillatory rotation to said clamping ring.

15. The earth working apparatus according to claim 9 wherein said clamping ring is selectively engageable with said cutting head, the selective engagement of said clamping ring with said cutting head permitting unidirectional rotation of the latter from the oscillatory rotation of the former.

16. The earth working apparatus according to claim 15 including an upper ring mounted on said cutting head above said clamping ring and selectively engageable with said cutting head, and said apparatus includes means interposed between said upper ring and said clamping ring for spacedly positioning said upper ring with respect to said clamping ring.

17. The earth working apparatus according to claim 16 wherein said upper ring includes hinged circumferential segments and a coupling means for pivoting said circumferential portions between a closed, cutting head engaging condition and an open non engaging condition.

18. The earth working apparatus according to claim 16 wherein said upper ring includes one or more peripheral slots to permit access to the interior thereof.

19. The earth working apparatus according to claim 16 wherein said means for spacedly positioning said upper ring comprises a plurality of circumferentially spaced, extensible means mounted on one of said upper ring and said clamping ring and coaxially abutting the other of said upper ring and clamping ring.

20. The earth working apparatus according to claim 19 wherein said extensible means comprises a plurality of hydraulic jacks.
